UNITED STATES PATENT OFFICE.

DIMITRI SENSAUD DE LAVAUD, OF NEW YORK, N. Y.

METHOD OF AND APPARATUS FOR WATER-COOLING CENTRIFUGAL PIPE-CASTING MACHINES.

1,299,918.

Specification of Letters Patent. Patented Apr. 8, 1919.

Application filed October 5, 1917, Serial No. 194,976. Renewed August 27, 1918. Serial No. 251,693.

To all whom it may concern:

Be it known that I, DIMITRI SENSAUD DE LAVAUD, a citizen of the United States of Brazil, residing at New York city, New

5 York, U. S. A., have invented new and useful Improvements in Methods of and Apparatus for Water-Cooling Centrifugal Pipe-Casting Machines, of which the following is a specification.

10 This invention relates to the casting of pipes or other hollow bodies of metal, by utilizing centrifugal force.

The object of the invention is to provide a method of and means for quickly and 15 evenly cooling all parts of the mold of a centrifugal casting machine, so that all parts of a comparatively long casting will be substantially uniformly cooled during the formation of the casting under centrifugal

20 force and during the solidification of the molten metal from which the casting is being made; thus making it possible to make better pipes and to increase the speed of manufacture.

25 Heretofore in the casting of pipes by the centrifugal method, attempts have been made to use temperature changes to facilitate the production of good castings. Some prior constructions have provided a

30 large annular water chamber sleeving only a comparatively small part of the pipe mold. Others have provided water spraying devices; but these have been utterly inadequate for the purpose. Others have provided thin 35 passages through which water is allowed to pass, but at such a rate and in such volume that the water at one part of the passage becomes heated before it can cool a part of the mold at another portion of the passage.

40 It should be understood that the cooling of the elongated pipe mold of a centrifugal molding machine handling molten metal, is a problem peculiar to itself and in no way analogous to the cooling of fixed bodies or 45 bodies not handling hot metal in its liquid condition. Some previous constructions have even attempted the use of temperature raising devices, as a line of gas-burners arranged exterior to the mold; but there is

50 very little doubt now, however, that the proper temperature treatment of the mold, during the formation of the pipe casting, is to cool the mold and the casting, as quickly and as uniformly as possible. The undersigned 55 has demonstrated by experiments that very fine results are obtained when the pipe cast-

ing is quickly and uniformly cooled; because then the rate of cooling may be arranged for in advance, and the casting may be withdrawn from the mold at a certain 60 predetermined temperature, to wit, a temperature equal to the temperature of the molten metal less the degrees of heat absorbed by the uniformly water-cooled mold, so that the pipe may then be subjected to 65 a higher predetermined temperature, to improve the quality of the casting to a remarkable degree, as described fully in my pending application, Serial No. 183,503, filed July 30, 1917.

70 I have discovered that the rotating mold of a centrifugal pipe casting machine may be quickly, adequately, substantially uniformly and controllably cooled, by means of a water jacket as long as or substantially as 75 long as the pipe mold and sleeving the mold from end to end. This cooling may be accomplished, I have found, by maintaining the water in the jacket, even when admitted at a single inlet, continuously in circulation 80 under suitable pressure. I have found that the circulating water may be fed into the jacket at only one point, that is, at one inlet, and the circulation thus maintained, thereby 85 continuously keeping the mold cool and at the same low temperature from end to end and in all parts, by making the water jacket of a certain minimum thickness, preferably at least as thick as or slightly thicker than the thickness of the wall of the pipe being 90 cast, while continuously feeding water at the jacket inlet under pressure, and by providing a water outlet or outlets for the jacket having a cross-sectional area less than 95 the cross sectional area of the inlet.

100 In other words, the essence of the present invention is the provision of an annular water jacket of some thickness to sleeve practically the entire length of the rotary mold of a centrifugal pipe casting machine, the jacket having an always open inlet and outlet (though valves may be provided to vary the relation between the cross-sectional areas of the inlet and outlet), and the continuous feeding of water to the jacket at the 105 inlet under sufficient pressure to predetermine that the water will be maintained in continuous circulation through the jacket at substantially constant pressure and substantially uniform temperature in all parts 110 of the jacket. The present invention was partially disclosed, among other things in

an application, Serial No. 131,064, filed jointly by myself and one Arens, November 13, 1916, and so at this point, opportunity may be taken to explain, to comply with the patent statute, that certain parts of the structure shown in the drawings hereof, and the inventions illustrated thereby, are more fully described and claimed in said application Serial No. 131,064.

10 The present invention will be more clearly understood from the following description, when taken in connection with the accompanying drawing illustrating the invention, in which drawing—

15 Figure 1 is a vertical longitudinal section taken approximately through the center of a centrifugal pipe casting machine;

Fig. 2 is a vertical transverse section taken approximately on the line 2—2 of Fig. 1, 20 showing propelling vanes which may be used for rotating the mold by means of the water circulation, details of the mold being omitted;

Fig. 3 is a vertical transverse section taken 25 on the line 3—3 of Fig. 1;

Fig. 4 is a vertical transverse section taken approximately on the line 4-4 of Fig. 1;

Fig. 5 is a view similar to Fig. 1, showing the left-hand end portion of the mold of a machine of slightly different construction than the machine of Fig. 1; and

Fig. 6 is a transverse vertical section taken on the line 6-6 of Fig. 5.

Referring first to Figs. 1 to 4, inclusive, 35 a shell 1, preferably made in sections, is suitably supported, as upon legs 2; a rotary mold 3 is disposed within this shell, preferably carried upon the ball-bearings 51.

The annular space between the mold 3 and the shell 1 is provided for a water jacket, 52, water in the jacket being kept continuously in circulation under suitable pressure as described herein in accordance with the invention. The water under pressure is in the present case admitted at a single inlet through the pipe 4 centrally located at the bottom of the shell. The water after cooling the mold passes from the machine by way of pipes 53 which may conveniently be located in the legs 2. Near each end of the mold 3 where the water leaves the water jacket chamber 52 are provided vanes 26 on the mold 3 and vanes 27 on the shell 1, forming a turbine, so that as the water is forced to circulate toward the pipes 53 the water acts upon these vanes 26 and reacts upon the vanes 27 to cause rotation of the mold.

According to this construction, the cross-sectional area of the inlet from the pipe 4 is made so much larger than the cross-sectional area of the space between the vanes 26 that, due allowance being made for the resistance to the circulation of the water exerted by the work done by the water in actuating the turbine, the water kept contin-

uously circulating in the water jacket chamber 52 is maintained under the proper pressure pursuant to the invention. In order that this pressure may be varied at the water inlet, the pipe 4 is provided with an adjustable valve 80. 70

In Fig. 1, the casting is indicated at T; as also in Figs. 3 and 4. It will be noted from Fig. 1 that the thickness of the water jacket chamber is over twice as great as the thickness of the pipe wall; and it is believed that best results are obtained when the thickness of the water jacket is at least as thick as the pipe wall of the pipe being molded in the rotating mold. 80

The maintenance of the circulation in the water jacket under pressure is of the essence of the present invention. Although the mold is rotating, and it is thereby moving its entire surface relative to the water in the jacket, this is not enough, as we have found that there is one part of the mold which is hotter than any other. This is the line, parallel to the axis of the mold, along which the metal is first poured. At the instant the metal is poured, steam forms itself on the outside of the mold, opposite the line along which the poured metal first hits the inside of the mold; and the adherence of the water to the mold, as this term may be used for want of a better one, is not absolute, but relative, that is, is not uniform. It has been observed that if an iron plate has thrown on it a little water, a portion of the water next to the plate will not vaporize immediately; it will form itself into little globules of water, which will begin to dance on the hot iron plate. The explanation of this is

that as soon as the water comes into contact with the hot plate, a certain quantity of steam forms itself between the iron and the water, which has the effect observed. The same phenomenon, I have discovered, is present in the case of the exterior surface of the mold of a centrifugal pipe-casting machine, occurring opposite the hotter longitudinal subdivision of the mold which first receives the metal. Unless the steam formation is suppressed so promptly and adequately that in effect it really never commences, serious difficulties arise. If the steam formation occurs along a particular portion of the mold, thus preventing the mold from being completely surrounded by water at every point, the mold contracts and expands at different portions different amounts and fatal distortion takes place. I have discovered that the steam formation may be suppressed, by maintaining the water in the jacket continuously in circulation, under pressure. The circulating water under pressure then exerts equal pressure against all parts of the mold, and sufficient pressure at the zone of possible steam formation, to throttle the formation of steam at 130

any point. No steam being formed, the condensation of this steam is not a problem. The entire mold from end to end is uniformly and adequately cooled, distortion of the mold cannot occur, and the casting is kept at an even temperature in all parts, thereby assuring that the casting will be flawless and may be subjected to a later heat treatment, if desired, depending on the temperature of the casting when removed from the mold. Such a heat treatment, as mentioned above, is explained in my certain pending application, filed July 30, 1917, Serial No. 183,503.

Referring now to Figs. 5 and 6, the casing 1 which houses the rotating mold 3, to provide the water jacket chamber 52, is provided with an open-bottomed hood 81, to the left of the left-hand end of the water jacket, for containing a plurality of buckets 83 circumferentially arranged on the left-hand end of the rotating mold 3. In this construction, as in the construction of Fig. 1, the cooling water is also used for providing power to rotate the mold 3; but whereas the water acted centrifugally on a turbine 26-27, the water here acts tangentially on a series of buckets. The water at the left-hand end of the water jacket 52 enters a nozzle-feeding chamber 84, by way of a passage 85, and passes through a nozzle 86 and impinges on the buckets to drive the rotating mold. The manually adjustable ball valve 87 is provided so the cross-sectional area of the large end of the nozzle 86 may be varied at will. This end of the nozzle may be considered the outlet of the water jacket circulation. In view of the fact that such a variable outlet is provided, a valve similar to the valve 80 of Fig. 1 may be omitted from the inlet to the water jacket. It will be noted that in the case of the construction of Fig. 1 the pressure of the constantly circulating water in the chamber 52 is controlled by a valve in the inlet (the valve 80 in the pipe 4), the cross-sectional area of the outlet, that is, the turbine 26-27, being practically constant. In the case of the construction of Figs. 5 and 6, it will be noted that the water is not used for doing the work of rotating the mold 3 until it has passed beyond a variable outlet in the water jacket arrangement, and so the pressure at the inlet, or in other words, the cross-sectional area of the inlet, may be maintained practically constant; reliance being placed upon the valve 87 for adjusting and controlling the pressure under which the circulating water is maintained during operation of the machine. It will of course be understood that in carrying out the invention the velocity of the circulating water need not necessarily be employed to do the work of rotating the mold 3; and in such case adjustable valves may be placed in either the inlet or the outlet or in both. In

practice, it has been found that excellent results are obtained when the cross-sectional area of the inlet is ten to forty times the cross-sectional area at the outlet, that is, when the velocity of the water issuing from the outlet is from ten to forty times as great as the velocity of the water flowing in at the inlet.

I claim:

1. In a centrifugal casting machine, the combination comprising an elongated rotary mold having a length several times greater than its maximum width, a shell extending circumferentially around said mold and arranged to form a chamber for the circulation of cooling liquid extending substantially from end to end of the mold, and means for maintaining the chamber full of cooling liquid under pressure.

2. In a centrifugal casting machine, the combination comprising an elongated rotary mold having a length several times greater than its maximum width, a shell extending circumferentially around said mold and arranged to form a chamber for the circulation of cooling liquid extending substantially from end to end of the mold, and means for maintaining the chamber full of cooling liquid under pressure in circulation, such means comprising a continuously open inlet and outlet and a valve in one of said inlet or outlet for varying the relation between the cross-sectional areas of the inlet and outlet.

3. In a centrifugal casting machine, the combination comprising an elongated rotary mold having a length several times greater than its maximum width, a shell extending circumferentially around said mold and arranged to form a chamber for the circulation of cooling liquid under pressure between said mold and shell, means for maintaining the chamber full of cooling liquid under pressure and in circulation, and means for controlling the flow of liquid to maintain the mold at a substantially constant temperature.

4. In a centrifugal pipe casting machine, the combination comprising a rotary mold having a length several times greater than its maximum width, a shell extending circumferentially around said mold and arranged to form a chamber for the circulation of cooling liquid extending substantially from end to end of the mold, and means for maintaining the chamber full of cooling liquid under pressure, said cooling chamber having a thickness at least as great as the wall thickness of the pipe cast by the machine.

5. In a centrifugal pipe casting machine, the combination comprising a rotary mold having a length several times greater than its maximum width, a shell extending circumferentially around said mold and ar-

ranged to form a chamber for the circulation of cooling liquid extending substantially from end to end of the mold, and means for maintaining the chamber full of 5 cooling liquid under pressure, said cooling chamber having a thickness approximately twice as great as the wall thickness of the pipe cast by the machine.

6. In a centrifugal casting machine, the 10 combination comprising an elongated rotary mold having a length several times greater than its maximum width, a shell extending circumferentially around said mold and arranged to form a chamber for the circulation 15 of cooling liquid extending substantially from end to end of the mold, and means for maintaining the chamber full of cooling liquid under pressure, said means including an inlet and an outlet so designed 20 that the velocity of the liquid issuing from the outlet is from ten to forty times as great as the velocity of the liquid flowing in at the inlet.

7. In a centrifugal pipe casting machine, 25 the combination comprising a rotary mold having a length several times greater than its maximum width, a shell extending circumferentially around said mold and arranged to form a chamber for the circulation 30 of cooling liquid extending substantially from end to end of the mold, and means for maintaining the chamber full of cooling liquid under pressure, said cooling chamber having a thickness at least as great 35 as the wall thickness of the pipe cast by the machine, and said means including an inlet and an outlet of such relative dimensions that the velocity of the liquid issuing from the outlet may be from ten to forty times 40 as great as the velocity of the liquid flowing in at the inlet.

8. In the art of centrifugally casting pipe and other hollow articles, the process of 45 cooling the rotary mold during casting, which consists in confining and guiding a flow of cooling liquid in contact with the surface of the mold opposite to the surface receiving the molten metal, while maintaining the liquid under pressure greater than 50 the pressure required to circulate the same.

9. In the art of centrifugally casting pipe and other hollow articles, the process of 55 cooling an elongated rotary substantially cylindrical mold during casting, which consists in confining a flow of cooling liquid under pressure in an annular sheet from end to end of the elongated mold and guiding the same in contact with the exterior thereof.

10. In the art of centrifugally casting 60 pipe and other hollow articles, the process of cooling an elongated rotary substantially cylindrical mold during casting, which consists in confining a flow of cooling liquid un-

der pressure in an annular sheet from end to end of the elongated mold and guiding 65 the same in contact with the exterior thereof, the annular sheet being at least as thick as the wall of the pipe being cast.

11. In the art of centrifugally casting pipe and other hollow articles, the process of 70 cooling an elongated rotary substantially cylindrical mold during casting, which consists in confining a flow of cooling liquid under pressure in an annular sheet from end to end of the elongated mold and guiding 75 the same in contact with the exterior thereof, the cooling liquid being thus confined and guided for contact with the exterior of the mold at a certain velocity, and being released from said confinement after 80 contact with the exterior of the mold at a velocity from ten to forty times as great as the first-mentioned velocity.

12. In the art of centrifugally casting pipe and other hollow articles, the process 85 of cooling an elongated rotary substantially cylindrical mold during casting, which consists in confining a flow of cooling liquid under pressure in an annular sheet from end to end of the elongated mold and guiding 90 the same in contact with the exterior thereof, the annular sheet being at least as thick as the wall of the pipe being cast, the cooling liquid being thus confined and guided for contact with the exterior of the mold at 95 a certain velocity, and being released from said confinement after contact with the exterior of the mold at a velocity from ten to forty times, approximately, as great as the first-mentioned velocity.

13. In a centrifugal casting machine, the combination comprising an elongated rotary mold the length of which is several times its greatest width, a shell extending circumferentially around said mold and arranged 105 to form a chamber for the circulation of cooling liquid under pressure between said mold and shell, means for maintaining the chamber full of cooling liquid under pressure and in circulation, and means for controlling the flow of liquid to maintain the mold at a substantially constant temperature.

14. In the art of centrifugally casting pipe and other hollow articles, the process 115 of cooling an elongated rotary substantially cylindrical mold during casting, which consists in confining a flow of cooling liquid in an annular sheet from end to end of the elongated mold and guiding the same in contact with the exterior thereof, while controlling the flow of liquid to maintain the mold at a substantially constant temperature.

In testimony whereof I have signed my name to this specification.

DIMITRI SENSAUD DE LAVAUD.
